UNITED STATES PATENT OFFICE.

MICHAEL J. MOLONEY, OF ROCHESTER, NEW YORK, ASSIGNOR OF ONE-HALF
TO JAMES A. MOLONEY, OF ROCHESTER, NEW YORK.

SHOE.

SPECIFICATION forming part of Letters Patent No. 691,284, dated January 14, 1902.

Application filed August 24, 1901. Serial No. 73,163. (No model.)

To all whom it may concern:

Be it known that I, MICHAEL J. MOLONEY, a citizen of the United States, residing at Rochester, in the county of Monroe and State 5 of New York, have invented new and useful Improvements in Shoes, of which the following is a specification.

My invention relates to improvements in the manufacture of shoes, and pertains to the 10 production of a turned-welt shoe as distinguished from the ordinary-welt shoe.

The primary object of my invention is to reduce the cost of manufacturing a welt-shoe and at the same time to produce a shoe which 15 is exceedingly flexible, and therefore highly desirable for shoes of all kinds, but especially adapted for children's and women's wear.

By means of this invention the insole and the upper are placed in such a position as 20 enables the workman to more readily and quickly sew the parts together. It saves the necessity of filling in between the insole and the outer sole in the ordinary-welt shoe in that when the shoe is ready to have the outer 25 sole attached thereto there is a smooth outer surface for the reception of the sole and a smooth inner surface for the foot of the wearer. There is a saving in the lasting operation, and finally a shoe is produced which 30 is when applied to spring-heel shoes absolutely nailless.

Referring now to the drawings, Figure 1 is a perspective view of a completed shoe embodying my invention, the same being shown 35 in section to illustrate the relative positions of the welt, the upper, the inner sole, the outer sole, and the stitches for uniting the several parts. Fig. 2 is an inverted plan view of the several parts placed upon the last and 40 tacked thereto ready to be stitched by means of a shoe-sewing machine. Fig. 3 is a transverse sectional view of the insole, showing the welt attached thereto and ready to be placed upon the last for the reception of the upper, 45 all of which are afterward sewed together. Fig. 4 is a transverse view showing the insole, the welt, and the upper in their positions upon the last and the parts stitched together. Fig. 5 is a top plan view of an upper, 50 showing the welt attached to the upper and ready to be placed upon the last, together

with the insole, as distinguished from the attachment of the welt to the insole, as shown in Figs. 3 and 4, the upper being shown right side out. Fig. 6 is a transverse view of the 55 upper turned wrong side out and after the welt has been attached thereto. Fig. 7 is a transverse view of the upper, the insole, and the welt sewed together and turned right side out and ready to receive the outer sole. 60

In the manufacture of my improved shoe the insole 1 is placed inside out upon the last 2 and the welt 3 is situated between the insole and the upper 4, as clearly illustrated in Fig. 4. The welt 3 in the method disclosed 65 in Figs. 3 and 4 is attached to the insole in any suitable manner before the upper is applied thereto for the purpose of preventing the displacement thereof under the final stitching operation in uniting the upper, the 70 insole, and the welt. As here shown, the preferred means of uniting the welt to the insole before the upper is applied is by means of a transverse row of fine stitching 9, though other means for uniting the welt to the sole 75 may be used. My preferred method, however, is to sew the welt 3 to the upper 4 before applying it to the insole, as shown in Fig. 5, instead of uniting it to the insole, as in Figs. 3 and 4. The welt having been attached in 80 inside out to either the insole or the upper by any desired means, as just described, the insole is placed inside out upon the last 2 and the upper turned inside out and tacked thereto by tacks 6, as shown in Fig. 2. 85

By reference to Figs. 3 and 4 it will be noted that in the positions of the parts the welt is entirely out of the way of the operator in sewing the welt and the upper to the channel 7 of the insole and that the parts are in 90 such a position as to be exceedingly convenient for the operator, which enables him to much quicker sew the parts together than is possible in the ordinary method of producing the ordinary-welt shoe, for the reason that in 95 the old method of making welt-shoes the upper is placed right side out and the welt extends in the form of a lateral flange, which is in the way of the operator and requires carefulness and skill to properly unite the parts. 100 In the use of my method this carefulness is not necessary, as the parts are in such a po-

sition that they are firmly held against displacement and there is no laterally-extending member in the way of the operator.

After the parts have been stitched together 5 by means of the stitches 8, which pass through the channel of the insole, the tacks having been removed, the projecting parts are cut off by any suitable implement very quickly, as in the position shown in Fig. 4, and the cutting 10 operation is conveniently performed. The result is a smooth inner surface, as illustrated in Figs. 1 and 7. The last is then removed and the shoe turned right side out, which produces a wide laterally-extending welt for 15 the attachment of the outer sole, as shown in Fig. 7, and produces an upper with the welt and the insole attached thereto that is remarkably flexible. It will also be noted from Fig. 7 that a smooth outer surface for the attachment of the outer sole is presented and that there is no filling in between the inner 20 and outer sole, as in the ordinary-welt shoe, thus producing a shoe which will wear better, as well as being cheaper to produce and more 25 flexible.

In the production of welt-shoes by the ordinary method it is well understood by those skilled in the art that the welt is not extended around the heel of the shoe and that the lower 30 edge of the heel of the upper is elongated and doubled around the heel portion and nailed to the inner sole, which requires considerable time, as well as producing a shoe inferior to one in which the sewing extends around the 35 heel portion as well as the foot and shank portions.

By reference to Figs. 1, 2, and 5 it will be noted that I prefer to extend my welt around the heel portion as well as the shank portion, 40 and owing to the relative positions of the parts when uniting them it is a convenient and easy matter to extend the welt all the way around the lower edge of the upper of the shoe, and thus leave a welt projecting 45 entirely around the shoe, by means of which the operator can sew the welt, the outer sole, and the heel, (in spring-heel shoes,) as well as the other portions of the shoe, thus producing a nailless shoe. This method will be pursued 50 also in the use of the projecting heel in that the outer sole will be preferably sewed to the welt all around the heel and then the heel nailed in position. This method of connecting the outer sole is found to be a considerable saving in time over the method used in 55 the ordinary-welt shoe, in which the welt extends only to the heel portion, and the lower edge of the upper is then doubled under the insole and nailed thereto, which method requires a filling in of the foot, the shank, and 60 the heel portions and after which the outer sole and the heel are nailed in position.

By reference to Fig. 4 it will be noted that my invention being used with an insole having 65 a flexible edge 5 enables the welt to extend downward between the sides of the last and the upper, thus taking up practically no

room, so that the same last which is used when the parts are sewed together in their reversed positions, as in Fig. 4, will fit the 70 shoe for lasting purposes when it has been turned right side out and still leave a wide projecting flange formed by the welt, as shown in Fig. 7, for the attachment of the outer sole by the usual sewing operation. 75

It is found in practice that my invention effects an enormous saving in the cost of the production of a welt-shoe in addition to producing a superior-wearing shoe and a shoe exceedingly flexible. It is also found in practice that I am enabled to produce a baby's 80 welt-shoe by means of my invention, something which has not been practical heretofore, thus producing for children, babies, and women a heavy-sole shoe practically as 85 flexible as the light-sole shoes heretofore made with the projecting-welt effect.

I am aware that heretofore turned shoes in which the upper has been attached to the outer sole have been produced, and am also 90 aware that a "mock" or "false" turned-welt shoe has heretofore been produced in which a welt is interposed between the upper and the outer sole and the parts then turned for the purpose of producing an imitation-welt 95 shoe. In this instance it will be noted, however, that the welt does not perform the function of uniting the upper and the insole to an outer sole, but performs no function whatever, simply remaining as an imitation. 100

My invention is essentially different from these prior turned shoes in that a shoe is produced in which the welt serves as a means to unite the outer sole after the shoe is turned right side out, which is not true of the previous turned shoes, thus making a new article in that I produce a turned-welt shoe and not what is known as a "turned shoe" or a mock or false turned-welt shoe. It will also be noted by reference especially to Figs. 3 110 and 4 that I prefer to use my invention in connection with an insole which has its edges tapered or cut away outward, as shown at 5, whereby the insole is provided with a projecting flexible flange that will bend and conform to the curve of the upper and welt when turned inside out, as in Fig. 4. This enables the same last to be used when the upper is either wrong or right side out and the size of the shoe to be accurately determined, which 115 is not true with a turned shoe or a turned mock-welt shoe, if the edge of the outer sole be extended any appreciable distance. 120

Having thus described my invention, what I claim, and desire to secure by Letters Patent, is— 125

1. A turned-welt shoe comprising an insole, a welt and an upper both attached to the inner face of the insole, the welt located between the insole and the upper and having 130 its outer edge projecting outward beyond the edge of the insole, and an outer sole attached to the projecting edge of the welt.
2. A turned-welt shoe comprising an insole

- having its edge tapered downwardly and outwardly, a welt and an upper seated against said tapered portion with the welt located between the insole and the upper, the outer 5 edge of the welt projecting and having its lower face substantially in a plane with the outer face of the insole, and an outer sole attached to the projecting portion of the welt.
3. A turned-welt shoe comprising an insole, 10 a welt and an upper both attached to the insole, the welt located between the insole and upper and having its outer edge projecting beyond the insole, and an outer sole attached to the welt.
- 15 4. A turned-welt shoe comprising an insole, a welt and an upper, both attached to the insole, the welt located between the upper and insole and extending entirely around the lower edge of the upper including the heel 20 portion and having its outer edge projecting

beyond the insole entirely therearound, and an outer sole sewed to the welt entirely around the upper including the heel portion, thus producing a nailless shoe.

5. A turned-welt shoe adapted to have its 25 insole, upper and welt connected wrong side out, the insole having a projecting flexible flange, the welt located between the upper and the flexible flange of the insole and having an outwardly-projecting portion when the 30 parts are turned right side out, and an outer sole attached to said outwardly-projecting portion of the welt.

In testimony whereof I have hereunto set my hand in the presence of two subscribing 35 witnesses.
